(57) **CLAIM**

I claim the ornamental design for a swivel knife handle, as shown and described.

DESCRIPTION

FIG. 1 is a top, rear perspective view of the swivel knife handle.

FIG. 2 is a bottom, front perspective view of the swivel knife handle.

FIG. 3 is a top view of the swivel knife handle.

FIG. 4 is a front view of the swivel knife handle.

FIG. 5 is a rear view of the swivel knife handle; and,

FIG. 6 is a right-side view of the swivel knife handle, which is a mirror image of the left-side view of the swivel knife handle.

The shading lines shown in the drawings represent the approximate three-dimensional contour of the design, and are not intended to indicate surface decoration.

The broken lines depict portions of the swivel knife handle in which the design is embodied that are not considered part of the claimed design.
